Des. 199,879
Patented Dec. 22, 1964

199,879

MARINE ENGINE

Richard W. Paxson, Columbus, Ind., Robert E. Graf, Tenafly, N.J., and Ernest M. Bevilacqua, Wilton, and Eliot F. Noyes, New Canaan, Conn., assignors to Cummins Engine Company, Inc., Columbus, Ind., a corporation of Indiana

Filed July 17, 1963, Ser. No. 75,850

Term of patent 14 years

(Cl. D77—1)

Fig. 3

FIG. 1 is a side elevational view of a marine engine embodying our new design;

FIG. 2 is a side elevational view of the opposite side of the engine shown in FIG. 1;

FIG. 3 is a top plan view of the engine;

FIG. 4 is an elevational view of one end of the engine;

FIG. 5 is an elevational view of the other end of the engine; and

FIG. 6 is a perspective view of the engine.

The dominant features of our design reside in the portions shown in full lines.

We claim:

The ornamental design for a marine engine, substantially as shown and described.
